UNITED STATES PATENT OFFICE

2,342,562

PROCESS OF PRODUCING IMPROVED
WETTING, SUDSING, AND DETERGENT
AGENTS

Nathaniel Beverley Tucker, Glendale, Ohio, assignor to The Procter & Gamble Company, Cincinnati, Ohio, a corporation of Ohio

No Drawing. Application December 12, 1941,
Serial No. 422,684

15 Claims. (Cl. 260—400)

This invention relates to a process for producing highly efficient sudsing, emulsifying and detergent agents.

More specifically, the present case relates to an improved process for the preparation of water-soluble salts of compounds of the following type

wherein $R\text{-CO}$ is an acyl radical having eight to twenty-two carbon atoms and R_1 is an alkylene or hydroxy alkylene radical having two to four carbon atoms. Illustrative compounds are the sodium salt of the oleic acid ester of isethionic acid ($C_{17}\text{H}_{33}\text{-CO-OCH}_2\text{H}_4\text{-SO}_3\text{Na}$) and the sodium salt of the coconut oil fatty acid (lauric acid predominantly) ester of 1,2-dihydroxy propane 3-sulfonic acid

These salts possess wetting, sudsing and detergent power in hard water, and in accordance with my invention are produced by the condensation of a salt of a higher fatty acid with a lower molecular weight halogen substituted alkyl sulfonate in the presence of certain amides or substituted amides as more fully hereinafter set forth.

It is an object of my invention to provide an improved method for the preparation of the above detergents. It is a further object to provide a process for the preparation of the above detergents which, as directly prepared, are free of products of side reactions, contain a higher proportion of the desired product, and which contain an enhancing agent for further improvement in sudsing and detergent power.

Other objects of my invention will be apparent from the following description.

In my copending application Serial No. 387,985, filed April 10, 1941, now U. S. Patent 2,289,-391 of which this application is a continuation-in-part, I have described and claimed a related process for producing compounds of the above type in which the soap and halogen substituted sulfonate are condensed in the presence of certain amides or substituted amides whereby the condensation reaction is facilitated and deficiencies of prior art methods of preparation, necessarily involving expensive purification after condensation, are obviated. In this process the effect of the amide or substituted amide is to promote the condensation by making the reaction mass fluid and miscible at temperatures below 200°

C. at about which temperature undesirable and harmful decomposition products are formed, as much as fifty to several hundred per cent based on the combined weight of the soap and halogen substituted sulfonate being employed to obtain the best results. The amides or substituted amides may or may not be removed from the reaction mix depending on whether or not the medium is objectionable from an odor, appearance or consistency standpoint and whether or not it is beneficial to the performance of the detergent in aqueous solution. Thus in the process of this copending application I am concerned with the use of amides or substituted amides which are volatilizable and which therefore may be removed from the reaction product at a temperature below that at which harmful decomposition products are formed.

In the present case I am not concerned with the selection of amides or substituted amides of suitable volatility but rather with those amides and substituted amides which not only promote the condensation between the soap and halogen substituted sulfonate but also act as enhancing agents for the sudsing and detergent power of the condensation product when allowed to remain admixed therewith. In addition the present case is concerned with the use of the amides and substituted amides in a range of proportions within which both of the above effects are obtained.

The amides which I use in practicing my present invention are those mono-amides formed from fatty acids having ten to fourteen carbon atoms and compounds selected from the group consisting of morpholine, ethanolamine, 1 amino 2,3 propane diol, ammonia and primary and secondary amines of the formula $HNR''R'''$ where R'' is alkyl and R''' is hydrogen or alkyl, the sum of the carbon atoms in R'' and R''' being less than 5.

In the preferred practice of my invention the soap is heated at elevated temperature with the lower molecular weight halogen substituted alkyl sulfonate in the presence of an amount of the amide or substituted amide which is sufficient to promote the reaction but which is below that amount detrimental to the detergent properties of the detergent formed when allowed to remain in admixture therewith. Such amounts are usually less than the optimum amount for condensation but even so, considerable benefit in promotion of the reaction between the soap and the halogen substituted sulfonate is realized with the smaller amounts, and even though the amide or

ubstituted amide were removed after the completion of the reaction the detergent product would be better than that formed under comparable conditions without its presence.

After the reaction has reached substantial completion, as may be determined for example by titration of a sample of the mix for ionic halogen, the reaction mix without further treatment may be cooled and/or formed into any of a number of desirable forms for use in laundering and other cleansing operations such as cakes, flakes, spray dried products, etc. Since the amides and substituted amides employed herein are also builders or enhancing agents for the detergents in that they improve their cleansing action, the products produced are far superior to any thus far prepared, as far as I am aware.

My invention will be more clearly understood from the following examples in which specific conditions of operation are set forth. However my invention is not limited to these specific conditions, as more particularly pointed out hereinbelow.

Example 1.—45 parts of dry sodium soap derived from coconut oil are mixed with 40 parts of sodium monochlorhydrin sulfonate and 24 parts of lauroyl morpholine in a reaction vessel which is not attacked by the reactants, such as glass-lined vessel for example. The mixture is heated with stirring at 135 to 140° C. for about 1½ hours, after which time the reaction between the soap and the monochlorhydrin sulfonate is substantially complete. The product, after cooling, is a white, stiff paste which dissolves in warm, hard water to give a clear solution possessing excellent detergent and sudsing power.

Example 2.—20 parts sodium monochlorhydrin sulfonate, 23 parts dry sodium soap derived from coconut oil and 12 parts of butyl lauramide are mixed in a reaction vessel similar to that employed in Example 1 at 150° C. for 1½ hours. The product as prepared dissolves substantially completely in warm hard water and possesses very good detergent power.

The materials and conditions of operation used in the above examples may be varied. For example, while I have shown the use of coconut oil soap, other soaps such as oleic acid soap and soaps of other fatty acids, individually and in admixture, having eight to twenty-two carbon atoms may be employed. Thus if desired, the stearates, palmitates, or myristates, or soaps from any of the natural occurring vegetable and animal fats and oils may be used. Also, it should be noted that in addition to alkali metal soaps, alkaline earth metal soaps such as calcium or magnesium soaps, or even some heavy metal soaps may be used, provided the metal is such that it readily combines with the halogen of the halogen substituted sulfonate to produce a neutral salt and provided that the metal does not form an insoluble salt with the condensation product.

In the examples I have shown the use of chlorine substituted sulfonates because these derivatives are readily available or easily prepared. However, a sulfonate substituted with any other suitable halogen, such as bromine, may be employed with equal ease without departing from the spirit of the invention.

The kind of metal ion in the halogen substituted sulfonate salt is relatively unimportant as long as the detergent agent, that is the condensation product, is water soluble. Thus, for

example, the alkali metals, sodium and potassium, and the alkaline earth metals, calcium and magnesium, may be employed since they form salts which are soluble in hard water.

5 The intermediate sulfonates, that is the halogen substituted sulfonates coming within the scope of the present invention, are those aliphatic compounds having two to four carbon atoms as above stated. Thus the following compounds in addition to those given in the examples may be employed—the sodium and potassium beta methyl monochlorhydrin sulfonates, sodium chlorethyl sulfonate, salts of chloro olefin sulfonic acids such as 2,chloromethyl propene 10 sodium sulfonate, and others which will be readily apparent to those versed in the art.

15 The amides and substituted amides employed in my invention do not take part in the reaction involved but promote the condensation, act as a flux in the formation of a fluid mixture of soap and halogen substituted sulfonate which may be readily heated and stirred without danger of localized over-heating and in addition enhance the performance of the condensation product as 20 a detergent in cleaning operations. Specific examples of amides and substituted amides which may be employed are the following:

N-lauroyl morpholine

30 Amide of capric acid

35 Amide of lauric acid

40 Monoethanolamide of myristic acid

Monoglyceryl amide of capric acid

45 Methyl lauramide

Ethyl lauramide

50 Monopropyl amide of capric acid

55 Monobutyl amide of capric acid

Dimethyl amide of myristic acid

60 Diethyl amide of lauric acid

Methyl ethyl amide of lauric acid

65 Methyl propyl amide of capric acid

70

75 Although I have listed above only amides which

are derived from specific fatty acids, it is to be understood that in the practice of the invention a mixture of amides derived from a mixture of fatty acids consisting predominantly of fatty acids having ten to fourteen carbon atoms such as may be obtained from coconut oil, palm kernel oil, and other oils of the coconut oil group may be employed.

The preferred temperature range for conducting the condensation reaction is 140 to 150° C., but of course the condensation may be carried out at temperatures outside of these limits. For example, some reaction is evident at temperatures as low as 130° C. and such low temperatures may be fully sufficient in some instances. Of course temperatures higher than 150° C. may also be employed, but temperatures substantially above 175° C. are usually unnecessary and may even be harmful since such high temperatures favor decomposition and the production of undesirable by-products.

The amount of amide or substituted amide which is employed in the present invention is that amount which is sufficiently large to promote the reaction between the soap and the halogen substituted sulfonate but which is not sufficiently large to be detrimental to the performance of the condensation product in laundering or other cleansing operations. Ordinarily I employ an amount of reaction medium which is from about fifteen per cent to about fifty per cent of the combined weights of soap and halogen substituted sulfonate and these are my preferred quantities. However, the range is not definitely fixed and I may find it desirable to use from about ten per cent to about one hundred per cent of the combined weight of the reactants.

Having thus described my invention, what I claim and desire to secure by Letters Patent is:

1. In the process of producing an improved wetting, sudsing, and detergent agent of the general formula

where $R \cdot CO$ is the acyl radical of a fatty acid having eight to twenty-two carbon atoms, R_1 is a radical selected from the group consisting of alkylene and hydroxy alkylene radicals having two to four carbon atoms and Me is a metal forming a water soluble salt, the step which consists in condensing a metal salt of a fatty acid having eight to twenty-two carbon atoms with a halogen substituted sulfonate of the general formula

where X is halogen and R_1 and Me are as above indicated, in the presence of a mono-amide of the formula $R \cdot CO \cdot A$, wherein $R \cdot CO$ is the acyl radical of a fatty acid having ten to fourteen carbon atoms and A is a radical selected from the group consisting of

R'' being alkyl and R''' being selected from the group consisting of hydrogen and alkyl, the sum of the number of carbon atoms in R'' and R''' being less than 5, the amount of the mono-amide being sufficient to promote the reaction but not

substantially greater than one hundred per cent based on the combined weights of the fatty acid salt and the halogen substituted sulfonate.

2. In the process of producing an improved wetting, sudsing and detergent agent of the general formula

where $R \cdot CO$ is the acyl radical of a fatty acid having eight to twenty-two carbon atoms, R_1 is a radical selected from the group consisting of alkylene and hydroxy alkylene radicals having two to four carbon atoms and Me is a metal forming a water soluble salt, the step which consists in condensing a metal salt of a fatty acid having eight to twenty-two carbon atoms with a halogen substituted sulfonate of the general formula

where X is halogen and R_1 and Me are as above indicated, in the presence of about fifteen per cent to about fifty per cent, based on the combined weight of the fatty acid salt and the halogen substituted sulfonate, of a mono-amide of the formula $R \cdot CO \cdot A$, wherein $R \cdot CO$ is the acyl radical of a fatty acid having ten to fourteen carbon atoms and A is a radical selected from the group consisting of

R'' being alkyl and R''' being selected from the group consisting of hydrogen and alkyl, the sum of the number of carbon atoms in R'' and R''' being less than 5.

3. The process of claim 2 in which the radical $R \cdot CO$ represents a mixture of acyl radicals corresponding to a mixture of fatty acids consisting predominantly of fatty acids having from ten to fourteen carbon atoms per molecule.

4. The process of claim 2 in which the mono-amide is derived from morpholine and a mixture of coconut oil fatty acids consisting predominantly of fatty acids having ten to fourteen carbon atoms per molecule.

5. The process of claim 2 in which the mono-amide comprises essentially N-lauroyl morpholine.

6. The process of claim 2 in which the halogen substituted sulfonate is monochlorhydrin sodium sulfonate.

7. The process of claim 2 in which the fatty acid salt is sodium coconut oil soap, the halogen substituted sulfonate is monochlorhydrin sodium sulfonate, and the mono-amide comprises essentially N-lauroyl morpholine.

8. Process of claim 2 in which the mono-amide is the amide of a mixture of coconut oil fatty acids consisting predominantly of fatty acids having ten to fourteen carbon atoms per molecule.

9. Process of claim 2 in which the mono-amide comprises essentially lauramide.

10. Process of claim 2 in which the fatty acid salt is sodium oleate and the halogen substituted sulfonate is monochlorhydrin sodium sulfonate.

11. Process of claim 2 in which the fatty acid salt is sodium oleate, the halogen substituted sulfonate is monochlorhydrin sodium sulfonate, and the mono-amide comprises essentially lauramide.

12. Process of claim 2 in which the mono-amide

is the monoethanolamide of a mixture of coconut oil fatty acids consisting predominantly of fatty acids having ten to fourteen carbon atoms per molecule.

13. Process of claim 2 in which the mono-amide comprises essentially the monoethanolamide of lauric acid.

14. The process of claim 2 in which the halogen

substituted sulfonate is beta methyl monochlorhydrin sodium sulfonate.

15. Process of claim 2 in which the fatty acid salt is sodium coconut oil soap, the halogen substituted sulfonate is beta methyl monochlorhydrin sodium sulfonate, and the mono-amide comprises essentially the monoethanolamide of lauric acid.

NATHANIEL BEVERLEY TUCKER.
